YARN DYEING MACHINE

Day K. Poole, New Hartford, N. Y., assignor to
Ainsworth Dyeing Machine Company, Inc.,
Utica, N. Y., a corporation of New York

Application June 5, 1940, Serial No. 338,966

3 Claims. (Cl. 68—203)

My present invention relates to a yarn dyeing machine and more particularly to a yarn dyeing machine where in practice the yarn is dyed generally but not necessarily intermittently as the yarn is being drawn by a winding machine from a series of cones generally of truncated form as produced by the yarn manufacturer, and said yarn after passing through or over the dyeing mechanism is rewound upon another series of spindles or cones forming a part of the winding machine in the factory or plant of the company which knits fabric from the rewound and dyed yard. Ainsworth's Patent No. 1,274,972 of Aug. 6, 1918, shows such a dyeing machine.

Since that patent a number of improvements or variations have been patented upon the dyeing mechanism or machines and it is so thoroughly common practice to utilize the drawing of the yarn by the winding machine for producing the necessary movement of the yarn in the dyeing machine that further illustration of the winding machine has become unnecessary in a patent upon a yarn dyeing machine.

The purposes of my present invention are to provide a yarn dyeing machine which is of new and improved form, construction, combination of its parts and operation of the device and to provide such a machine which is more economical in construction, assemblage and repair and yet which is stronger and more sturdy and durable in construction and operation, and further to provide such a machine which is cleaner and especially more free from the leaking of the dyeing liquid or fluid, and also freer from the deposits upon the machine of the lint always present in the air in a factory where yarn is being rapidly moved, and to provide a machine which prevents the accumulation or deposit of this lint upon parts of the dyeing machine close enough to the operating parts or to the moving yarn thereof as to overcome the liability of accumulations of such lint catching upon the yarn or falling upon the yarn and being transferred on the yarn into the cone where the yarn is being rewound.

A further purpose is to provide covers or protectors over the working mechanism of the different units of the dyeing machine for preventing the deposit upon the yarn of lint or the deposit of lint upon some parts of the machine close enough to be drawn to and upon the yarn. These covers or protectors are extensive enough to protect a whole unit and the covers are preferably made in sections with one section easily swinging up from its normal position so as to give access to the machine.

A further purpose is to provide in such a dyeing machine such a reorganization of the necessary parts of the machine as will tend to accomplish certain of the purposes above mentioned and particularly to provide a construction which is simpler, cleaner, more durable in use and adapted to be operated longer without requiring cleaning of the machine.

Through the successive developments of yarn-dyeing machines of this type more mechanism has been mounted within or upon the tubular reservoir; in fact up until my present invention it has seemed to be the practice to consider the tubular reservoir as the structural element of the dyeing machine and to which tubular reservoir may be secured not only the means for carrying the dye-carrying felt wheels but all of the rest of the incidental parts that could be attached by screws or brackets or similar means or by such screws or brackets fastened along the length of the tubular reservoir. This has resulted in the tubular reservoir being a constant source of annoyance and repair and stoppage of the machine for repair or for cleaning. The tubular reservoir while being in effect a tube and so relatively strong for thus being the burden-bearer of the whole machine had walls so thin that every screw to be attached thereto required a hole to be first bored through the thin metal of the tubular reservoir, and then this hole tapped with a thread for the attachment of the desired bolt or screw. In view of the fact that the regular solvent of all these dyes or stains used in a dyeing machine is alcohol or some similar very penetrating solvent, it will be readily understood that all of these numerous holes required special treatment to prevent their quickly leaking. It has become the common practice to put special material around the threaded part of the screws or to put a quantity of white lead or the like under the head of the screw or the bracket held down by the screw in order to prevent leakage of the dye fluid. On the other hand the vibration of the moving parts of the machine, while not violent, is constant and tends to break the leak-proof quality of all of the joints upon the tubular reservoir. The leaks thus started allow the escape of the dye fluid which soon tends, even if the leak is small, to put a layer of dye material about the outside of the tubular reservoir and about all the parts connected thereto. If the leaks become larger through neglect or otherwise they form a source of considerable leakage of dye, and of even coating more quickly the outside of the tubular reservoir and its connected parts with the dye.

The solvent from the dye soon evaporates and leaves a thicker paint-like coating around the reservoir and its attached parts, which soon become loaded with the floating lint from the room and it becomes that much harder to keep the machine clean and free from dripping dye.

After the series of Ainsworth patents upon dyeing machines, one of the most decided improvements was that shown in the Coleman Patent 1,583,577 of May 4, 1926, upon a yarn dyeing machine where the felt dye-carrying wheels rotating on an axis transversely of the tubular reservoir were rotated by a longitudinal shaft located outside of the tubular reservoir (as distinct from within and even down in the dye as in some of the best previous machines), but even in this Coleman machine there was for every "end" or yarn being dyed a large hole cut through the side of the tubular reservoir through which hole extended the horizontally arranged shaft extending out from said felt wheel to a point outside the reservoir where it was operatively connected to the longitudinally extending driving shaft. Inner and outer screw-threaded blocks were provided surrounding said shaft to make a tight joint, but this series of holes through the side of the reservoir obviously added appreciably to the risk of leakage and obviously required a shutting down of the whole machine if repairs had to be made upon the mechanism of one unit. Some of the purposes of this present invention are to overcome the disadvantages and difficulties of previous machines along the line just indicated and affirmatively it is one object of this invention to provide a construction wherein the dye-carrying felt wheels are mounted upon an axis above the top of the tubular reservoir and the felt wheels project down through an opening in the top of the reservoir into contact with the liquid dye and thus I avoid cutting through the sides of the reservoir for the passage therethrough of the short shaft carrying the dye wheel.

Furthermore in remedying many of the defects of preceding machines and as a positive improvement I have provided a yarn-dyeing machine wherein the tubular reservoir performs only its necessary function of being a reservoir for the liquid dye but ceases to be the mechanism-supporting and burden-carrying part of the machine because I provide separate strong structural frame members particularly well equipped to bear the strain of not only the weight but of the rotation of the various parts and which frame members support all of the parts comprising the different units of the machine and said frame members even carry the weight of the tubular reservoir itself. From these strong frame members are supported, as will be hereinafter described, all of the pieces and parts of the units of the machine, providing convenient and ample support and attachment for all these parts without having to puncture the tubular reservoir with a single hole (except of course the slot in the top of the reservoir for each of the felt wheels to project downwardly therethrough). These supporting frame members also furnish convenient support for the covers over the several units and particularly for the pivotal support of one-half of each pair of covers of a unit. By thus completely reorganizing a dyeing machine of this character I have been able to provide a more economical machine to build in the first place and particularly a more convenient machine to assemble, and I also provide a more

durable machine in operation, meaning thereby either for normal operation of all the units or for repair of any particular unit when such occasion comes.

5 With my machine it is entirely practicable to readily take out of operation any given unit without having to stop the whole machine. When the parts of a unit have been thus disconnected they can be repaired or another unit substituted and replaced on the machine either without stopping the machine at all or under some circumstances, with a very short stoppage of the usual continuous operation of the machine.

10 15 Further purposes and advantages of my invention will appear from the specification and claims herein.

Fig. 1 is a vertical transverse sectional view through a unit of a yarn dyeing machine embodying my invention, the section shown being mostly along the axis of the felt wheel and its short transverse shaft, that is substantially along the line 1—1 of Fig. 2.

20 25 Fig. 2 is a top view of a unit of the machine shown in Fig. 1, but with the protecting covers of the unit removed to better show the details of the machine.

30 35 Fig. 3 is a cross section through the machine on line 3—3 of Fig. 2 and looking towards the left, that is towards the side of the unit, so as to show better the arrangement of the frame members and their attached parts for supporting the parts of the unit and even the tubular reservoir. The movable cover is swung to its upward position.

35 40 45 Fig. 4 is a top or plan view showing the longitudinal frame of my yarn dyeing machine adjacent one of the dyeing units, with the other frame members adjacent that unit, but omitting the covers and the parts mounted thereon, and showing the adjacent portion of the tubular reservoir only diagrammatically by long dash lines and with one corner of the top plate cut away and a part of the side frame member under said cut away part of the top plate being also eliminated in order to show more plainly the shape of one end of a bolster.

45 50 55 Fig. 5 is a top or plan view of one unit of the machine with the covers down in place and showing in dotted lines the outline of certain of the principal parts of the unit that are under cover. Said view also shows the near edges of the covers of the units to both sides of this unit.

Fig. 6 is a side elevation of the central section 55 60 of the upper portion of the swinging cover separate from the rest of the machine.

Fig. 7 is a detail sectional view on line 7—7 of Fig. 6 but showing the swinging cover in engagement with the fixed cover and held there by the spring catch 75.

60 Referring to the drawings in a more particular description it will be seen that the machine has two strong, longitudinally extending vertically arranged side frame members 10 and 11, long enough to support the desired number of dyeing units, it being understood that the said side frame members 10 and 11 will be suitably rigidly supported at their opposite ends either by separate supporting means therefor or more commonly by the proper parts of the frame of the yarn winding machine upon which the dyeing machine is assembled, and by suitable supports provided along the longitudinal frame intermediate its ends.

Beside these side frames 10 and 11 the machine

as a whole has the usual tubular reservoir 13 of the proper length for the number of units included in the machine, and a longitudinally extending drive shaft 14 for driving the dye-applying means hereinafter shown as the several dye-carrying felt wheels 15, one for each unit of the machine. A unit of the machine is understood to be the parts necessary for applying in the usual intermittent way (or non-intermittent way if desired) the dye from the reservoir 13 to the dye-wheel 15 and to the length or "end" of yarn being passed over the dye-wheel 15.

For each unit of the dyeing machine there is provided an arch-shaped top plate 12 and a pair of spaced bolsters 16. The opposite ends of the top plate 12 rest down upon the top of the frame members 10 and 11 and the arch-shaped bottom 17 fits throughout the length of the plate upon the curved upper side of the tubular reservoir 13. Each bolster 16 has the upper face of its opposite ends bear directly against the lower edge of the two side frame members 10 and 11 while the central portion of the said bolster has an upwardly extending part 18 in the top of which there is a curved longitudinally extending groove or recess 19 adapted to fit and placed so as to set against the curved bottom of the reservoir 13.

Just within each side frame 10 or 11 near each corner of the top plate 12 is placed a headed bolt 20, the enlarged head of which bears against the bottom face of the bolster 16 at that end of the top plate while the adjacent shank portion of the said bolt 20 extends up through a hole 21 provided near the opposite ends of said bolster. The upper ends of each of these bolts is screw-threaded and projects into a threaded hole 22 or the mechanical equivalent provided in the top plate 12 just inside the side members 10 or 11. It will be seen that when these bolts 20 and the bolsters 16 and the top plate 12 are assembled and the bolts tightened up, the said reservoir will be rigidly located and securely held in place by the said side frame members 10 and 11 and the said bolsters and top plate 12 will also be rigidly supported in place by said side frames 10 and 11 and that said bolsters and top plate 12 are thus secured without any apertures having to be provided through the reservoir for the location or support of said bolsters or top plate, and particularly that said bolsters and especially the top plate are well adapted to provide parts and rests and supporting elements for the attachment thereto of all the other necessary parts of the unit of the machine without having to make holes, slits or apertures of any kind into the wall of the reservoir. The central right hand portion of the top plate 12 is provided with a thickened ridge upstanding from the bottom line of the said plate 12 to provide in the upper portion of said ridge a transversely extending hole 24 extending from end to end thereof and forming a bearing for the location therein of the short transverse shaft 25 upon the inner end of which is supported the felt dye-carrying wheel 15. The mounting of said dye wheel on said inner end of the shaft is commonly had by the extreme inner or left hand end of said shaft being of a reduced diameter so as to form a shoulder 26 on the inner large part of the shaft against which may first be set a metal or other suitable washer 27, and then the said felt wheel 15 and then a retaining nut 28 which is clamped against the wheel by being screwed up upon the threaded extremity at the inner end of the inner small portion of said shaft 25. The portion of the

arch-shaped plate 12 that is to be adjacent said dye wheel 15 is provided with a box-like rectangular-shaped housing 29 surrounding said dye wheel 15 and open at its bottom and also at its top. The bottom opening of this housing 29 coincides with the slot 30, formed in the top of the reservoir 13 and extending longitudinally of said reservoir for the purpose of having the lower portion of said dye wheel 15 project downwardly through said slot 30 into the dye, which in practice nearly fills the reservoir so that the dye wheel, by having its lower portion project down into the dye more or less as shown in Fig. 1, is well supplied with dye. The upper portion of the wheel projects above the top of the housing 29 so that the yarn 31 passing crosswise of the dyeing machine and cross-wise of the upper part of the said dye wheel 15 may receive dye from said wheel when the said yarn is allowed to drop against the wheel in an obvious manner by the rotation of the projecting wings 32 successively bringing them to horizontal position, as the knocker shaft 33 is rotated. It will be seen that the said housing 29 forms a complete guard all about the central and larger portion of the felt dye wheel 15 and, by reason of the tight fit and the suitable sealing as by white lead or the like of the arch-shaped plate 12 upon the reservoir 13 adjacent the slot 30 in the tubular reservoir at the bottom of said housing 29, the escape of any of the dye liquid around the wheel is prevented even though there might be at times a surging action along the top of the liquid in the reservoir.

The outer or right hand end of the transverse shaft 25 is provided with a miter wheel 34 in engagement with a similar miter wheel 35 on the drive shaft 14. It will now be seen that I have provided a dyeing machine construction of the type indicated where the dye wheel 15 is mounted on a shaft above the reservoir and extending transversely thereof but without said shaft having to project into the reservoir and without the reservoir having to be punctured for fastening the bearing of said shaft in place relative to the reservoir.

Spaced longitudinally respectively from the outer ends of the top plate 12 and on the right hand half of the machine as seen in Figs. 1 and 3, there are provided two cover-supporting brackets 36 which conveniently are formed as metal plates more or less of the shape shown in side elevation in Fig. 3. Each plate is of somewhat irregular shape and has formed, preferably integral therewith, an outstanding bracket 37 towards its bottom and on its outer surface, viz. its vertical face that is away from the plate 12. At its lower right hand corner as shown in Fig. 3 the plate 36 is provided with a notch 38 forming a downwardly facing step adapted to bear directly against the top edge of the right hand frame member 11, the other side of the notch providing a shoulder adapted to bear against the inner face of the frame member 11 near its top. On the left hand lower portion of the plate 36 as seen in Fig. 3 there is provided a curved face 40 fitting closely against the adjacent outer circular face of the reservoir 13. A bolt 41 has its head below an apertured ear 42 projecting from the side of the bolster 16, with the shank of said bolt 41 going up through said ear 42 and having its upper end screw-threaded and engaging the screw-threaded aperture in the ear 37 on the plate 36. In this way the bracket plate 36 is securely and rigidly locked so that its upper edge 43 is on the same level as the top

of the housing 29. The other cover-supporting bracket 36 consists of a similarly shaped and secured plate beyond the other longitudinal end of the top plate 12, of which only the upper edge 43 and its corresponding integral bracket 37 appear in Fig. 2. As best appears in Fig. 2 the two cover-supporting brackets 36 are provided on their inner faces, at their tops, with inwardly extending ears 44 either in the form of two closely spaced ears or one wide ear on each bracket plate 36 so as to provide holes 47 spaced inwardly from the bracket plates 36, which holes 47 are screw-threaded and as shown hereinafter, are utilized in fastening the fixed cover down in place and preferably incidentally also the holes upon one cover-supporting bracket are utilized for fastening in place the yarn guides herein-after described.

Resting flat upon the upper edges 43 of the plates 36 and upon the upper faces of the ears 44 is placed the main and flat portion 48 of the fixed cover 49. An edge view of this cover 49 appears in Fig. 3, which edge view also shows the curved and down-turned portion 59 of the cover extending out over the drive shaft 14 and the miter gears 34 and 35 on the transverse shaft 25 and drive shaft 14 respectively. The holes 47 already mentioned in the two ears 44 and appearing in Fig. 2, are to receive the shanks of headed screws 46 that project down through aligned holes formed in the said flat portion 48 of the fixed cover 49. Preferably the inner edge 52 of the cover 49 also rests upon the near side of the upper surface of the housing 29 and in practice this edge of the cover may project up very close to the near face of the dye wheel 15, as plainly appears in Fig. 3. In this Fig. 3 there appears, in its upswung position, the other or movable cover 53. In Fig. 3 an end or edge view of this movable cover appears, and in Fig. 1 the said cover appears in transverse sectional view, in its normal or down position. This cover may most conveniently be formed of a piece of sheet brass or other suitable material pivotally mounted at its lower and outside or left hand side as the cover appears in Figs. 1 and 3. This pivotal mounting may conveniently be formed by the lower left hand portion of the two ribs 54, which follow the inner face of said swinging cover 53 and are rigidly secured thereto, being loosely pivoted on a hinge rod 55, which is in turn mounted towards its opposite ends upon the left hand bracket plates 56. These bracket plates 56 are very similar, except in size, to the bracket plates 36 already mentioned in that the bracket plates on this left hand side of the machine as shown in Fig. 3, have a notch 57 in their lower face whereby the lower face is definitely located against the upper face of the left hand frame member 16 at the inner side of the said frame member. The inner ends of these bracket plates 56, as plainly appears in Fig. 3, have a curved face 58 adapted to and closely bearing against the adjacent curved outer face of the reservoir 13. These bracket plates 56 are each provided with an outstanding ear 59 having a screw-threaded aperture which receives the screw-threaded upper end of a headed bolt 60, the head of which bears against the bottom face of the apertured ear 61 projecting outwardly from each bolster 16 at the ends of the unit.

From the hinged lower edge of the cover 53, the said cover projects directly upwardly until it reaches about the level of the lower part of shaft 33, where the said cover is curved to the

right, but still extending upwardly, until it comes to a point directly above said shaft 33, from which point the cover extends horizontally straight to the right as shown in Fig. 1, well above the rotating wings 32 and also well above the dye-carrying wheel 15. Beyond the dye-carrying wheel this swinging cover curves downwardly and has a short vertical portion reaching to the fixed cover 49. At the lower end of said vertical portion the movable cover is provided with an outwardly extending and horizontally disposed flange 39, which flange is adapted to rest down flat upon the fixed cover 49 a little way to the right of the inner edge 52 thereof. It will now be seen that the fixed cover 49 and the movable cover 53 form a very effective covering and guard extending over the parts of the dyeing unit that are movable, such as the shaft 33 and its wings 32, and over the dye wheel 15, and over the surfaces of the dyeing unit upon which lint is most apt to gather. These two covers also extend well beyond the adjoining stationary or movable parts of this unit of the dyeing machine and in that way protect the unit that much more from the deposit of lint thereupon.

The extent of the fixed cover and of the swinging cover is shown in the transverse sectional view Fig. 1, and in the end view Fig. 3. The lengthwise extent of the two covers however is plainly shown in Fig. 5 by solid lines for both the fixed cover 49 and the swinging cover 53. From this showing in Fig. 5 it will be particularly noted that both covers extend well beyond the cover-supporting members 36 and thus serve as a wider reaching lengthwise protection against the deposit of lint on any part of the unit of the dyeing machine. Furthermore it will be noted that the swinging cover when in its normal or down position very thoroughly protects the dye wheel 15 itself from lint and also protects the nearby upper edge of the housing 29 from deposit of lint thereon, which is especially advantageous because accumulations of lint on the upper edge of the housing 29 might easily drop over into the opening of the housing about the dye wheel and then the dye-moistened lint might adhere to the periphery of the dye wheel and become attached to the yarn 31 passing across the dye wheel. Such clots of dye-saturated lint are particularly objectionable when deposited upon the passing yarn 31 as they make a bad spot upon the yarn and an enlargement thereon which is carried by the dyed yarn on to the receiving cone and there the dye from the "slub" of dye-saturated lint is transferred to adjacent lengths of yarn for several layers and produces a darker colored spot due to the excess of dye present. It will be noticed that both the covers and the downwardly extending overhanging parts on the outer edges thereof protect the dyeing unit from lint that may be carried laterally of the machine. Furthermore not only are the two halves of the cover of a dyeing unit longer than the longitudinal extent of the dyeing mechanism proper, but as is plainly shown in Fig. 5 the covers of the different units of the dyeing mechanism on a dyeing machine are practically continuous lengthwise of the machine. The covers of one unit come to within $\frac{1}{2}$ of an inch of meeting the covers of adjoining units lengthwise of the machine. In this way it will be seen that any given unit of the dyeing mechanism is protected not only by its own set of covers but is protected also by the covers of the adja-

cent units lengthwise of the dyeing machine, so that there is really no opportunity for lint to be deposited on a unit through air currents passing lengthwise of the dyeing machine. In fact the covers of the adjoining dyeing units come just as close together as they can and still allow for the upward swinging of the movable cover or for the separate assembling or disassembling of the several units of the dyeing machine. The space between adjoining covers of adjacent units is so slight that no lint can in practice pass downward therethrough, but the operatives in cleaning the dyeing machine can wipe the tops of the covers lengthwise of a considerable part of the dyeing machine and entirely ignore the very slight space of appreciably less than $\frac{1}{32}$ of an inch between the covers of adjoining units.

As both the fixed cover 49 and the swinging cover 53 are composed of either flat or smoothly curved polished surfaces, it will be evident that lint deposited on top of or against any of the outer surfaces of these covers can be readily removed even when the machine is in operation. Also the swinging cover can be readily swung to its upper position, thus exposing all of the knocker device and its shaft, and the adjacent side of the housing 29 and of the reservoir for the cleaning of those parts when necessary.

Located on top of the fixed cover 49 is a bracket 62, angle-shaped in transverse section. The horizontal web 63 of the bracket rests flat upon the fixed cover and is secured in place as by headed screws 46 projecting therethrough conveniently down into the holes 47 already mentioned as provided in the upper side of the ears 44. Conveniently these screws thus serve not only to hold this bracket 62 in place but also to hold the fixed cover.

From the upstanding web 64, towards its outer and right hand end as seen in Fig. 1, there extends horizontally a long yarn guide 65, beneath which runs the yarn 31 being dyed. The outer end of this long guide 65 is bent upward (see Fig. 5 near numeral 65) for convenience in threading the yarn upon the dyeing machine. To the left of the long yarn guide 65 as the parts are seen in Fig. 1 there is provided upon the upstanding web 64 of the bracket 62 a swingingly mounted arm 66 carrying at its inner end a shorter yarn guide 67, which projects horizontally for a short distance and then has its outer end turned up as suggested by the angular arrangement of said guide 67 in Fig. 5. The said arm 66 is pivoted at its outer end to the said web 64 as by a screw 68 projecting through the arm 66 into the web 64. A slot 69 is provided in the arm 66 just to the right of the shorter yarn guide 67 and a headed screw 70 projects through this slot into the web 64 whereby, in an obvious manner, after the arm 66 has been set to the right position vertically to give the correct adjustment to the shorter yarn guide 67 the setting up of said screw 70 will hold said arm and thereby said shorter yarn guide permanently in desired position.

Through the portion of the swinging cover 53 that is above the level of the flange 39 of said cover and above the level of the knocker shaft 33 there is provided a slot 71 for the passage, transversely of said cover, of the yarn 31 being dyed by the machine. At both ends of this slot there are provided enlargements 72 and 73 at the right hand and left hand ends respectively as seen in Fig. 1 which allow for the up and

down movement of the yarn being dyed, as the yarn is raised by the knocker wings 32 and allowed to fall again against the dye wheel 15.

As a further precaution against lint descending through this slot onto the yarn beneath the cover, said slot slants to the left as it extends upwardly from the said enlargements 72 and 73, as appears by the separate side view Fig. 6 of the movable cover 53. It will thus be seen that 10 lint that may happen to drop through the horizontal portion of the yarn slot 71 that extends directly across the upraised flat part of the cover, in dropping straight down will not fall upon the yarn itself since that yarn, as will be obvious 15 from the diagrammatic showing thereof in Figs. 5 and 6, is not directly below the horizontal part of the slot 71.

In my machine the tubular reservoir is not subjected to the strain or vibration of having to support the driving shaft or having to be perforated to have mounted thereon brackets for the support of the driving shaft. In my machine the longitudinally extending frame and especially the side frame member 11 has rigidly secured thereto and projecting therefrom brackets 78 which at their upper outer ends carry bearings, preferably ball bearings 79, for the support of the drive shaft 14. The lower ends of these brackets have inverted L-shaped plates, the short ends of which angle-shaped plates rest flat upon the top surfaces of this side frame member 11 while the longer angle of the plate engages the outer face of the said frame member and is securely bolted thereto.

In a similar manner the other side frame member of the longitudinal frame provides support for the knocker shaft 33, as by having a similar bracket 80 carry suitable bearings at its upper end for said knocker shaft while the lower part of said bracket has a similar L-shaped plate, the long leg of which bears flat against the whole outside face of this side frame member 10 and is secured thereto by suitable screws or bolts while the short arm of the L-shaped plate of the brackets rests solidly against the top surface of this frame member.

In practice the swinging cover 53 is held firmly down in its lowered position, preferably by spring operating catches conveniently consisting of tapered pins 75 projecting downwardly from the flange 39 of said cover 53. The pins 75 have recesses 76 in their outer sides immediately below the said flange 39. These pins project into openings 77 provided in the fixed cover immediately below said pins at or near the edge. As the outer sloping sides of these pins engage the outer edge of the opening 77 in the fixed cover the parts of the swinging cover carrying the pins are sprung away until the recesses come opposite the metal of the fixed cover, when the said pins can spring outwardly or to the right as the machine is seen in Figs. 1, 3 and 7.

What I claim as new and desire to secure by Letters Patent is:

1. In a yarn-dyeing machine for use in a lint-laden atmosphere, the combination of a horizontally arranged tubular reservoir having a restricted longitudinal slot in its upper portion, a top plate fitting down upon the top of the reservoir and having an upright box-like housing open at its top and bottom and having its open bottom registering with the said slot in the reservoir, said top plate having a transverse bearing extending from one exterior side of the plate to said housing on a level above the reservoir, a

shaft mounted in said bearing and having its inner end extending into the chamber of said housing, a dye wheel placed in said housing through the open top thereof and mounted on the inner end of said shaft and with its upper portion projecting above the top of the housing and with its lower portion projecting downwardly through said slot into the reservoir, means for rotating said shaft, knocker means for moving the yarn into and out of engagement with said dye-wheel, and a protector extending over said knocker means, said dye-wheel and said open-topped housing and preventing the deposit of lint upon said dye-wheel and into the open top of said housing.

2. In a yarn-dyeing machine for use in a lint-laden atmosphere, the combination of a horizontally arranged tubular reservoir having a restricted longitudinal slot in its upper portion, a top plate fitting down upon the top of the reservoir and having an upright box-like housing open at its top and bottom and having its open bottom registering with the said slot in the reservoir, said top plate having a transverse bearing extending from one exterior side of the plate to said housing on a level above the reservoir, a shaft mounted in said bearing and having its inner end extending into the chamber of said housing, a dye wheel placed in said housing through the open top thereof and mounted on the inner end of said shaft and with its upper portion projecting above the top of the housing and with its lower portion projecting downwardly through said slot into the reservoir, means for

rotating said shaft, knocker means for moving the yarn into and out of engagement with said dye wheel, and an inverted trough-like protector extending up over said knocker and said dye wheel and having its opposite depending sides provided with apertures for the free normal passage therethrough of the yarn to and from said knocker and said dye wheel, said protector shielding said dye wheel and said open-topped housing from the deposit of lint thereon and therein.

3 In a yarn-dyeing machine the combination of a horizontally disposed longitudinally extending main weight-carrying and strain-bearing frame, a tubular reservoir horizontally arranged adjacent said frame and having a restricted longitudinal slot in its upper portion but with its sides otherwise imperforate, other frame members carried by said main frame and clampingly engaging said reservoir and holding it in place, said other frame members including a top plate fitting down upon the top of the reservoir and having an upright box-like housing having its open bottom registering with the said slot in the reservoir, said top plate having a transverse bearing extending from one exterior side of the plate to said housing on a level above the reservoir, a shaft mounted in said bearing having its inner end extending into the chamber of said housing, a dye wheel located in said housing and mounted on the inner end of said shaft and with its upper portion projecting above the top of the housing, and means for rotating said shaft.
